(57) CLAIM

The ornamental design for a cleaning brush and holder set, as shown and described.

DESCRIPTION

FIG. 1 is a top plan view of a cleaning brush and holder set showing the design;

FIG. 2 is a bottom plan view thereof;

FIG. 3 is a left elevation view thereof;

FIG. 4 is a right elevation view thereof;

FIG. 5 is a front elevation view thereof; and,

FIG. 6 is a rear elevation view thereof.

The broken lines depict portions of the cleaning brush and holder set that form no part of the claimed design.
